SIGHT

James S. Stewart, Swampscott, Mass., assignor to
The Lyman Gun Sight Corporation, Middle-
field, Conn., a corporation of Connecticut

Application April 10, 1935, Serial No. 15,581

7 Claims. (Cl. 33—47)

My invention relates to a sight, and more especially to a front sight of the interchangeable insert type wherein an insert or reticule is positioned within a hood in such manner that it may be readily removed when it is desired to substitute another insert.

It has heretofore been proposed to make use of inserts having circular peripheral edges which closely fit the cylindrical bore of a hood, and thus centralize the sighting apertures of the inserts, rotational movement of the inserts being prevented by lateral projections on the inserts, which engage longitudinally directed faces on the hood. The inserts, of these prior forms of front sights, have generally been held within the hoods by being clamped between a shoulder, within the hood, and a threaded plug, mounted in the hood and forcing the inserts against the shoulder. One of the principal objects of the present invention is to bring about a form of sight in which the use of threaded plugs, or other movable or detachable parts for holding the inserts within the hood, is eliminated.

A more specific object of the invention is to bring about a form of sight of the interchangeable insert type in which the inserts may be inserted and removed without the use of tools.

A feature of the invention resides in a form of hood and insert therefor in which there are no projecting parts on the insert extending beyond the hood surface.

It is considered desirable, in sights intended for use in target shooting, to position the sighting part of the insert within the hood in as deep a shade as possible and another object of the invention is to prevent, substantially if not entirely, the entrance of light into a hooded sight of the above character, except through the ends thereof.

To these and other ends, the invention consists in the novel features and combinations of parts to be hereinafter described and claimed.

In the drawing:

Fig. 1 is a side elevation of a sight according to the invention, on an enlarged scale;

Fig. 2 is an end view of the sight shown in Fig. 1;

Fig. 3 is a sectional view taken along line 3—3 of Fig. 1;

Fig. 4 is an end view of one form of insert suitable for use in connection with the invention;

Fig. 5 is a view similar to Fig. 3 but showing the insert in the position it occupies at the beginning of the movement of insertion;

Fig. 6 is a view similar to Fig. 4 but showing an insert having a different type of sighting member;

Fig. 7 is a view similar to Fig. 4 but showing a modification, and

Fig. 8 is a view similar to Fig. 4 but showing another modification.

Referring now to the drawing in which I have illustrated my invention by showing a preferred embodiment of the same, the reference numeral 10 indicates, in general, the improved sight which includes a hood 11, and an insert 12. The hood 11, in this instance, takes the form of a hollow cylinder having a bore 13, of circular cross-section, a vertical transverse opening or slot 14, and a dove-tail base 15, the particular type of base forming no part of the present invention. The bottom of slot 14 is defined by the flat horizontal faces 16 and 17, which are spaced a substantial distance above the center line or axis of hood 11.

The insert 12, mounted within the hood, as shown in Figs. 1, 2, and 3, is of a thickness to closely fit the slot 14, and consists of a circular edge portion 18, concentric with respect to sighting aperture 19 and of the same radius as the bore 13 of the hood, the circular edge portion 18 extending circumferentially a distance substantially greater than a semi-circle and, in the instance shown, contacting with the lower part 25 of bore 13, throughout an arc of more than 180° and extending from the inner end 20, of hood face 16, to the inner end 21, of hood face 17, and terminating at laterally outwardly directed horizontal shoulders 22 and 23, which contact with faces 16 and 17, of the hood. Above the shoulders 22 and 23 the insert is provided with a peripheral edge of the same radius as the outer surface of the hood, the peripheral edge 24, of the insert, being flush with the outer surface of the hood, when mounted therein. The contact of insert edge 18, with the bore 13, centralizes the sighting aperture 19, in the hood, the contact between the shoulders 22 and 23, and hood faces 16 and 17, preventing rotational displacement of the insert and insuring that the post 25, of the insert, will be vertical.

Due to the reason that the arcuate length of edge 18 is greater than that of a semi-circle of equal radius, the distance between the inner ends 20 and 21, of hood faces 16 and 17, is substantially less than the diameter of the insert across the edge 18, as for example, between the points 26 and 27. For this reason upward movement of the insert out of slot 14 is opposed by contact of the inwardly curving wall of the hood above the center line with the edge 18, of the insert, above points 26 and 27.

The insert 12 is made out of resilient material, preferably steel, and in actual practice will be stamped out of sheet material, the stamping process removing a substantially ring-like piece of the material in the space 28, to form the sighting aperture ring 29 and a ring-like outer body 30, the inner edge 31, of the latter being concen-

tric with the edge 18. The ring-like outer body 30 is resilient and is compressed inwardly to remove the insert, the outer end of shoulder being cut away, as at 32, to permit the insertion of the 5 corner 33, of another insert, to be inserted thereunder for lifting or prying movement. When sufficient lifting pressure is applied to the insert that the wall of the hood, above the center line may compress the ring-like body 30, the insert 10 may be sprung upwardly out of the hood. The new insert is placed in the hood in a reverse manner, that is to say, it is placed in the position shown in Fig. 5, the edge 18, of the insert, contacting with the inner ends 20 and 21, of hood 15 faces 16 and 17, pressure on the upper end of the insert causing the ends 20 and 21 to spring the ring-like body 30 inwardly, until it can pass the edges 20 and 21, whereupon the insert snaps downwardly into the hood, the body 30 expanding 20 to bring the edge 18 into contact with the hood bore 13.

In practice the shooter is supplied with a number of inserts having different sizes of apertures or these may take the form of the insert 25 34, of Fig. 6, in which a post 35 replaces the aperture 19, each insert, except for the sighting portion, having the same form and being interchangeable in the hood. It will be noted that the edge 24 of the insert does not extend beyond the 30 outer surface of the hood so that there are no projecting parts apt to catch on the lining of a gun case or the like. For this reason, as well as for the reason that the slot 14 is very narrow, the chance of pressure being exerted on the 35 insert of an amount and in the proper direction to force the insert out of the hood, is extremely remote. It will be further noted that the insert closes the slot 14 so that no light may pass through the slot into the hood.

In Fig. 7, I have shown a modification of the 40 insert in which the upper end of the latter is cut away, as at 36, to give added resiliency to the body 30, and in the form shown in Fig. 8 this has been carried to the extent of making the 45 insert in the form of a split ring, the insert 37 having a ring-like body 38, cut away above the aperture ring 39, to form a gap 40, the adjacent ends 41 and 42, of the body 38, moving into and closing the gap during the compression of the 50 insert as the latter is inserted or removed. With this form it will be found possible to locate the shoulders 43 and 44 at a greater distance above the center line of the hood and insert, than is possible with the form shown in Fig. 4.

While I have shown and described a preferred 55 embodiment of my invention, it will be understood that it is not to be limited to the details shown, but is capable of modification and variation within the spirit of the invention and the 60 scope of the appended claims.

What I claim is:

1. A front sight comprising, a hood having a cylindrical bore and a vertical transverse slot, and an insert mounted in the slot and having a 65 circular edge portion extending downwardly into and fitting the bore and in continuous contact therewith below the slot circumferentially of the bore a distance greater than 180°.

2. A front sight comprising, a hood having a 70 cylindrical bore and a vertical slot extending downwardly into the hood, the slot where it intersects the hood walls forming oppositely disposed horizontal faces each of which is above the longitudinal axis of the hood, and a sight 75 insert mounted in the slot, said insert having a

circular edge portion contacting with the lower part of the hood bore from one of the slot faces to the other and shoulders engaging the slot faces.

3. A front sight comprising, a hood having an axially directed opening extending from end to end and an opening extending downwardly into the first opening, and an insert, said insert including a resilient compressible body which may be assembled into the hood through the downwardly extending opening, the greatest width of the downwardly extending hood opening being less than the width of the insert body whereby the latter is compressed to pass through the downwardly extending opening, the axially directed opening below the bottom of the downwardly extending opening being shaped to permit expansion of the insert body. 5 10 15

4. A front sight comprising, a hood having a cylindrical bore and a slot extending downwardly 20 into the upper part of the hood and intersecting the bore at right angles, the slot forming faces in the hood wall, the hood faces being above the axis of the bore, and a sight insert mounted in the slot and extending downwardly into the bore, 25 said insert having a resilient body contacting with the bore below the faces circumferentially thereof through an arc greater than 180°, and means on the insert contacting with the hood faces to prevent rotational displacement of the 30 insert in the hood.

5. A front sight comprising, a hood having a cylindrical bore and a slot in the upper part of the hood intersecting the bore at right angles and terminating in oppositely disposed horizontal faces in the hood wall which are above the bore axis, and a sight insert mounted in the slot and extending downwardly into the bore, said insert having a resilient body, the resilient body having a circular edge portion below the faces 35 which contacts with the wall of the bore below the faces circumferentially from one face to the other, and said body having an edge portion above said faces which is flush with the exterior of the hood. 40

6. A front sight comprising a hood having a cylindrical bore and a slot extending downwardly 45 into the upper part of the hood and intersecting the bore at right angles, the slot forming faces in the hood wall, the hood faces being above the longitudinal axis of the bore, and a sight insert mounted in the slot and extending downwardly into the bore, said insert having a resilient body contacting with the wall of the bore below the faces circumferentially thereof through an arc greater than 180° and shoulders formed on the 50 insert and contacting with the hood faces, one of the shoulders being cut away to permit the insertion of a suitable instrument between the shoulder and adjacent face for prying the insert 55 out of the hood. 60

7. A front sight for a gun comprising, a hood having a cylindrical bore the axis of which is longitudinally of the gun and a vertical transverse slot extending downwardly into the hood, the bottom edges of the slot being above said longitudinal axis of the bore, and a sight insert mounted in the hood in the slot, said insert including a circular edge portion extending through more than 180° and fitting the bore circumferentially thereof between the bottom edges of the slot, and shoulders on the insert engaging the bottom edges of the slot. 65 70 75
